UNITED STATES PATENT OFFICE.

JOHN WILLIAM WOLFE AND JOSEPH ALBERT SNOW, OF SHENANDOAH, IOWA.

PIANO-HOIST.

1,267,952.

Specification of Letters Patent.

Patented May 28, 1918.

Application filed April 7, 1917. Serial No. 160,509.

To all whom it may concern:

Be it known that we, JOHN WILLIAM WOLFE and JOSEPH ALBERT SNOW, citizens of the United States of America, residing at 5 Shenandoah, in the county of Page and State of Iowa, have invented certain new and useful Improvements in Piano-Hoists, of which the following is a specification.

This invention relates to a piano hoist 10 and has for its principal object the production of a structure so formed as to permit a piano to be lifted upon the body of the conveying vehicle or to be easily lifted therefrom and deposited upon the ground or 15 other suitable support.

Another object of this invention is the production of a piano hoist in which a movable platform is carried upon a frame, the frame, of course, being fixed upon the body 20 of the vehicle and being provided with suitable means for lowering or raising the movable platform upon which the piano is to be carried, thus permitting the piano to be lowered upon the ground or lifted on to the 25 vehicle so as to be carried thereby when desired.

Another object of this invention is the production of a piano hoist wherein simple 30 and efficient means is provided for efficiently bracing the entire construction, thus precluding any possibility of the accidental collapsing of the structure when a piano is carried thereon.

A still further object of this invention is 35 the production of a piano hoist wherein simple and efficient means is provided for rapidly, although gently, moving the platform to a desired position when a piano is carried thereon.

With these and other objects in view this 40 invention consists of certain novel combinations, constructions, and arrangements of parts as will be hereinafter fully described and claimed.

45 In the accompanying drawings:—

Figure 1 is a side elevation of the piano hoist as constructed in accordance with this invention showing the same mounted upon a vehicle.

50 Fig. 2 is a rear elevation of the piano hoist when ready for use.

Fig. 3 is a central vertical section through the piano hoist.

Fig. 4 is an enlarged fragmentary sectional view taken on the line 4—4 of Fig. 1. 55

Fig. 5 is a section taken on the line 5—5 of Fig. 12.

Fig. 6 is a section taken on the line 6—6 of Fig. 1.

Fig. 7 is a section taken on the line 7—7 60 of Fig. 2.

Fig. 8 is a section taken on the line 8—8 of Fig. 3.

Fig. 9 is a section taken on the line 9—9 65 of Fig. 1.

Fig. 10 is a section taken on the line 10—10 of Fig. 1.

Fig. 11 is a section taken on the line 11—11 of Fig. 1.

Fig. 12 is an enlarged fragmentary perspective view of a portion of the movable platform. 70

Referring to the accompanying drawings by numerals it will be seen that the piano hoist is adapted to be carried upon a frame 75 1 of an automobile, as herein disclosed which, of course, is supported by the springs 2 carried by the axle 3 and wheels 4. While the device as herein disclosed is shown as applied to an automobile it is, of course, 80 obvious that the structure is intended and capable of being used in connection with any other suitable vehicle.

The supporting frame comprises the longitudinal beams 5 which are positioned upon the frame 1 of the supporting vehicle and these beams 5 are fixedly retained in position by means of the bolts 6 having nuts 7, which bolts 6 are passed through the frame 1, as clearly shown in Fig. 3. The standards 90 8 are fixedly mounted by means of the bolts 9 intermediate the ends of the beams whereby these standards are fixedly carried in set positions. The braces 10 are carried by means of the bolts 11 upon the longitudinal beams 5 and are retained in engagement with the standards 8 in any suitable manner so that these standards will be greatly reinforced when in use. From this construction it may be seen that a very rigid frame 95 100 has been provided for supporting the weight of the piano when the hoist is in operation.

The movable platform comprises the parallel inner bars 12 and outer bars 13, these bars 12 and 13 being connected by the transverse bars 14 and 14' at their ends, while 105

- the strips 15 are carried by the bars 12 and 13 extending transversely thereacross, as clearly shown in Fig. 2. These bars and strips may be secured together in any suitable manner so as to form a rigid frame. It should be noted that the inner bars 12 extend for a considerable distance beyond the lower transversely extending bar 14' and have their lower ends connected by means of 10 the bar 16 so that the retaining brackets 17 which are of L-shaped construction in elevation are secured upon the ends of the bars 12 and adjacent the ends of the bar 16 so as to project above the upper surface of these 15 bars so that when a piano is positioned upon the movable platform it may bear upon these brackets 17. The arms 18 are pivotally mounted upon the bolts 19 carried by the beams 5, as shown clearly in Fig. 10 20 so that the arms 18 will be carried in spaced relation and adjacent each side of the frame. The central bars 12 are provided with bearing blocks 20 upon their lower surface which bearing blocks 20 are retained in position 25 by means of set screws 21 passing therethrough and also into the bars 12, as clearly shown in Fig. 7. The supporting rod 22 passes through the upper ends of the arms 18 and has its ends carried by the blocks 20. 30 It will be seen that this rod 22 is held against accidental displacement by means of the nuts 23 so as to cause the upper ends of the arms to be pivotally secured to the movable platform.
- 35 When the movable platform is carried upon the frame as shown in Figs. 1, 2, and 3 the lower end of the frame will be resting upon the beams 5, while the upper end of the frame will be supported by the upper 40 ends of the arms 18 and the standards 8. The frame will be in an inclined position so as to support very easily a piano, as indicated in dotted lines in Fig. 1 while the standards 8 will not be broken from their 45 position inasmuch as they will be greatly reinforced by means of the braces 10.
- Bearing blocks 24 are secured by means of the bolts 25 upon the longitudinal beams 5 and carry a rotating shaft 26. This shaft 50 26 has a drum 27 shrunk thereon or keyed in position in any suitable manner so that when the shaft 26 is rotated the drum 27 will also rotate in unison therewith. The ends of this shaft 26 pass through the bearing blocks 24, as clearly shown in Fig. 11 55 so that a gear 28 may be shrunk or keyed in any suitable manner upon the shaft 26 for purposes to be hereinafter set forth.
- The operating shaft 29 having a crank 60 30 is keyed to the pinion 31 which meshes with the gear 28, as shown clearly in Figs. 1 and 2. The shaft 29 is firmly carried upon the beams 5 by means of the retaining clamps 32 carried upon these beams and 65 embracing the shaft, as shown in Fig. 10.

Thus, it will be seen that as the shaft 29 is rotated rotary movement will be imparted through the pinion 31 and gear 28 to the rotating shaft 26 so as to cause the drum 27 to rotate.

A starting cable 33 is connected to one end of the eye 34 secured to one of the strips 15. This starting cable 33 is wound upon the drum 27, as shown in Figs. 2 and 3, so that as the drum is rotated in a desired direction 70 the starting cable 33 will be partially wound thereon, thus starting the movable platform to slide upon the longitudinal beams 5 adjacent their rear ends. In order to prevent this platform from tilting, however, the 75 lifting cables 35 are secured to the eyes 36 carried by the central beams 12 and then passed around the pulleys 37 carried with in the slots 38 formed in the bar 16 connecting the lower ends of the bars 12. The lifting cables 35 then pass so as to be wound upon the drum 27 as shown in Figs. 2 and 3. When the frame moves downwardly and the drum is being rotated in a counter-clockwise direction it will be seen that the 80 lifting cables 35 will unreel therefrom so that the downward rearward pulling of the starting cable 33 will cause the lower end of the movable platform to begin to slide upon the beams 5 adjacent their rear ends, as 85 above set forth. After the movable platform is moved over the end of the fixed frame it will be seen that the movable platform will ride upon the rollers 39 rotatably mounted upon the rear ends of the beams 5, 100 as clearly shown in Fig. 2. Thus, it will be seen that since the upper end of the movable platform will be carried upon the arms 18 the arms will be swung rearwardly for supporting the upper end of the frame and 105 causing the same to move correctly in a downward direction although the action of the lifting cables 35 will cause the movable platform to move as slowly or rapidly as desired whereby when a piano is carried 110 thereon it may be "eased" very slowly until it rests upon the ground or a support, as shown in dotted lines in Fig. 1. It is, of course, obvious that when the piano is carried upon the movable platform suitable securing cables or bands may be passed around the piano so as to engage the U-bolts 40 carried upon the side portions of the movable platform, as shown clearly in Fig. 2. After the lower end of the platform rests 115 upon the ground or other support the piano may be released and tilted to an upright position very easily.

When this device is in operation it will be seen that the drum 27 may be rotated so as 120 to cause the movable platform to be moved downwardly by the swinging rearwardly and downwardly of the arms and the extension of the lifting cables 35. After the lower portion of the platform has engaged 125

130

the ground it will be seen that a piano may be placed in engagement therewith by resting upon the supporting brackets 17. The piano may then be tilted rearwardly into engagement with the platform, after which the securing bands may be passed around the piano and into engagement with the bolts 40 whereby the piano will be positively carried upon the platform. By the rotation 10 of the drum in a clockwise direction it will be seen that the lifting cables will be wound thereon, while the starting cable 33 will be unreled, thus permitting the movable platform to be lifted upwardly, while the swinging 15 of the arms will cause the platform to be swung over onto the frame to the position indicated in Fig. 1. Thus, it will be seen that the platform will be positively carried upon the frame so as to efficiently 20 support the same, thus permitting a piano to be transported when desired. It will be seen that the structure is so formed as to permit a single piano to be carried upon the vehicle at a single time.

25 It is, of course, obvious that this structure may be employed for carrying large slabs of stone or blocks of marble, if so desired, for the movable platform is of such a construction as to permit a piano, or stones, or 30 blocks of marble to be secured thereon and moved upwardly upon the frame so as to be transmitted without danger of accidental displacement.

From the foregoing description it will be 35 seen that a very simple and efficient piano hoist has been produced which is so formed as to readily lift the piano from the ground up on to the supporting frame or to remove a piano from the supporting frame and 40 lower the same very gently upon the ground, or other supporting structure, while simple and efficient means has been provided for lifting or lowering the movable platform as readily as desired, while the construction of 45 the arms is such as to cause the platform to be moved over onto the frame owing to the swinging of the arms over to one side when in use.

What is claimed is:—

50 1. In a device of the class described, the combination of a supporting frame, said frame being adapted to be carried upon a vehicle, arms pivotally mounted upon said frame, a platform pivotally secured to said 55 arms, whereby said platform will be carried in a tilted position when upon said frame, means for limiting the movement of said arms in one direction, whereby said platform will have its upper end efficiently sup- 60 ported, means for starting said platform to move over the end of said frame, and means for gently lowering said platform into engagement with the ground or other supporting structure, said last-mentioned means 65 being adapted to lift said platform up-

wardly causing said arms to swing the lower end of said platform upon said frame.

2. In a device of the class described, the combination of a frame, said frame comprising a pair of longitudinally extending 70 beams, vertical standards carried by said beams, braces carried by said beams and secured to said standards intermediate their ends for reinforcing said standards, arms pivotally mounted upon said beams, a platform pivotally secured to the upper ends of said arms, whereby the upper end of said platform may rest against the upper ends of said standards, thereby causing the movement of said arms in one direction to 80 be limited, whereby said platform will be carried in a tilted position when upon said frame, means for starting said platform to move over the ends of said frame, and means for gently raising or lowering said plat- 85 form.

3. In a device of the class described, the combination of a plurality of longitudinally extending beams, vertical standards carried by said beams, braces carried by said beams 90 and engaging said standards for reinforcing the same, arms pivotally mounted upon said beams, a platform pivotally connected to the upper ends of said arms, a drum mounted upon said beams, a starting cable connected 95 to said platform and engaging said drum, means for rotating said drum in either direction, whereby said cable may be wound upon said drum, lifting cables connected to said platform and being wound upon said 100 drum, whereby when said starting cable is wound upon the drum the lifting cables will unreel therefrom permitting the platform to move downwardly very gently into engagement with the ground, said drum being 105 adapted to be rotated in the opposite direction so as to wind the lifting cables thereon and unreel the starting cable, whereby the platform will be lifted upwardly causing the arms to swing upwardly and then forwardly thereby causing the lower end of 110 the platform to rest upon the rear portions of the beams.

4. In a device of the class described, the combination of a plurality of longitudinally 115 extending beams, vertical standards carried by said beams, means for reinforcing said standards, arms pivotally mounted upon said beams, a platform positioned upon said beams, supporting blocks carried by said 120 platform, a rod carried by said supporting blocks, said rod passing through the upper ends of said arms, whereby said platform will be pivotally mounted upon said arms, and means for raising and lowering said 125 platform.

5. In a device of the class described, the combination of a plurality of longitudinally extending beams, vertical standards carried by said beams, means for reinforcing said 130

- 4
- standards, arms pivotally mounted upon said beams, a platform positioned upon said beams, supporting blocks carried by said platform, a rod carried by said supporting blocks, said rod passing through the upper ends of said arms, whereby said platform will be pivotally mounted upon said arms, a drum rotatably mounted upon said beams, means for rotating said drum, a starting cable connected to said platform and wound upon said drum, lifting cables connected to said platform and wound upon said drum, whereby when said drum is rotated in one direction said starting cable will be drawn downwardly and rearwardly upon said platform as the lifting cables are being unreeled whereby said platform may be moved gently down into engagement with the ground, said drum being adapted to unreel said starting cable and reel said lifting cables so as to cause said platform to rest upon the forward portions of said beams being guided by said arms.
6. In a device of the class described, the combination of a plurality of longitudinally extending beams, vertical standards carried by said beams, means for reinforcing said standards, arms pivotally mounted upon said beams, a platform positioned upon said beams, supporting blocks carried by said platform, a rod carried by said supporting blocks, said rod passing through the upper ends of said arms, whereby said platform will be pivotally mounted upon said arms, bearing blocks mounted upon said beams, a rotating shaft carried by said bearing blocks, a drum keyed upon said shaft, a gear keyed upon said shaft, a drive shaft

secured to said beams, a pinion keyed upon said drive shaft and meshing with said gear, means for rotating said drive shaft, whereby rotary motion will be imparted through said pinion and gear to said rotating shaft so as to cause said drum to be rotated, a starting cable connected to said platform and being wound upon said drum, lifting cables connected to said platform and being wound upon said drum, whereby when said drum is rotated said cables will be operated so as to either move said platform to a lowered position or to a position upon the frame.

7. In a device of the class described, the combination of a frame, arms pivotally secured to said frame, a platform pivotally secured to said arms, said platform being larger than said arms, means for lifting said platform, said arms being adapted to guide said platform upon said frame, whereby the lower end of said platform will rest upon said frame, for relieving considerable of the supporting strain from said arms, and standards carried by said frame in the path of movement of said arms, whereby said arms will engage said standards when moved in one direction, so as to be limited in their movement, thereby holding said platform in a set position.

In testimony whereof we affix our signatures in presence of two witnesses.

JOHN WILLIAM WOLFE.
JOSEPH ALBERT SNOW.
